Primary Examiner — Cynthia M Chin(74) *Attorney, Agent, or Firm* — Simpson & Simpson, PLLC(57) **CLAIM**

The ornamental design for a toy element, as shown and described.

DESCRIPTION

FIG. 1 is a top perspective view of a toy element of the present invention;

FIG. 2 is a front perspective view of the invention shown in FIG. 1;

FIG. 3 is a rear perspective view of the invention shown in FIG. 1;

FIG. 4 is a top perspective view of the invention shown in FIG. 1;

FIG. 5 is a bottom perspective view of the invention shown in FIG. 1;

FIG. 6 is an outside perspective view of the invention shown in FIG. 1; and,

FIG. 7 is an inside perspective view of the invention shown in FIG. 1.
